OIL BATH SOLENOID

Hollis W. Jencks, Ferndale, and Edmond A. Viale, Southfield Township, Oakland County, Mich., assignors to Detroit Coil Company, Ferndale, Mich., a corporation of Michigan

Filed May 7, 1956, Ser. No. 583,323

18 Claims. (Cl. 317—185)

This invention relates to solenoids and particularly to an oil bath solenoid.

This is a continuation-in-part application of our earlier filed application, Serial No. 479,331, filed January 3, 1955, and now abandoned.

Through the last few decades, an electrically operated device termed a solenoid has come into widespread use for actuating small mechanical devices. The solenoid comprises generally a coil of wire adapted to be coupled with a source of electric power, with a plunger disposed adjacent the coil to be attracted theretoward or thereinto upon energization of the coil. The plunger is either coupled with or adapted to abut the device to be actuated by the solenoid. Countless varieties of uses have been made of solenoids, frequently in machines for applications wherein the solenoid is called upon to be operated many thousands or millions of times in the space of a few months or a year. In many of the uses to which solenoids are put, they are located in relatively inaccessible places requiring, for example, substantial disassembly of the associated machinery in order to repair or replace worn or inoperative parts of the solenoid. Frequent repair or replacement of solenoids so located obviously is undesirable both from the standpoint of the cost of parts needing replacement and the time and effort involved in making the replacement necessitated by the disassembly of machinery in which the solenoid is located, but also through loss of the use of the machinery within which the solenoid is located.

There are a number of factors determinative of the life of the solenoid. Of these two are of prime importance, viz. the rapidity with which heat is conveyed away from an operating solenoid and the amount of shock imposed on the solenoid during its operation caused by the sudden arrests of the plunger's movement at opposite ends of its stroke. Unless the heat generated by the solenoid during its operation is conveyed away as rapidly as it is formed, the temperature of the solenoid will rise, and if the temperature exceeds the melting point of insulation on the wire comprising the coil, the coil will short out and proper operation of the solenoid will be impaired if not altogether prevented.

The shock encountered by the plunger at its sudden arrested movements at opposite ends of its stroke, tends to break up the plunger after extended operation. The meeting surfaces of the plunger and solenoid supporting frame which come together as the plunger is sucked into the solenoid, wear away, which, as more fully explained hereinafter, eventually has a very harmful effect on the solenoid's operation.

Any solution to these problems, however, in order to gain commercial favor, must be intensely practical and must be embodied in a structure capable of manufacture at a cost which, though exceeding the cost of conventional solenoids, is far less in proportion to the increased light span of the solenoid. The improved solenoid also must be capable of being mounted for operation in a

2

simple manner and in the same positions and after the same fashion as a conventional solenoid.

Therefore, an object of our invention is the provision of a solenoid unit having a life span far exceeding that of a conventional solenoid, and which may be manufactured at a cost substantially less for its life span than a conventional solenoid.

An object of our invention is the provision of a solenoid unit which may be mounted, after the fashion of the conventional solenoid, directly upon a device to be actuated, such as a valve, switch, or the like, and which unit comprises an oil bath within which the solenoid operates, with the oil bath, the solenoid, and a fluid sealing means, all compactly housed and novelly arranged with respect to each other.

Another object of the invention is the provision of a solenoid unit adapted to be mounted upon a device to be actuated, and which unit will convey away a substantial portion of heat developed through the operation of the solenoid, and thereby permit a greater amount of electric current to be passed through the solenoid than is ordinarily possible without overheating the solenoid.

Another object of the invention is the provision of a solenoid unit of the above-mentioned character which will function over a much greater length of time and through a substantially greater number of cycles than will the conventional solenoid, and in which the movement of the plunger of the solenoid is damped at the extreme opposite ends of its stroke.

Another object of the invention is the provision of an oil bath solenoid which is mounted upon and removed from the device to be actuated as a unit, and in which the operating mechanical connection between the unit and the device to be actuated as well as the electrical connection for energizing the unit are automatically effected when the unit is placed upon and secured to the device, and are automatically disconnected when the unit is unfastened and removed from the device. With the attainment of this object, the installation and removal of an oil bath solenoid unit requires the attention of only one workman, such as a hydraulics mechanic, where the device is a hydraulic valve. Heretofore, the installation or removal of a solenoid on any hydraulic equipment required the attendance, under union regulations, of an electrician to connect or disconnect the wires, and a hydraulics mechanic to connect or disconnect the securing means holding the solenoid on the equipment.

In one form of the invention the solenoid itself is resiliently mounted within a housing and held in place within the housing against one end wall thereof by spring means bearing against the solenoid and against an opposite end wall of the housing, with the housing adapted to be secured to the device to be actuated.

Another object of the invention is the provision of a solenoid unit which is adapted to be mounted on a device to be actuated, and which unit includes an enclosure open at one end and within which a solenoid coil and plunger are disposed, with the enclosure filled with oil enveloping the solenoid, and with a flexible diaphragm closing the open end of the enclosure and adapted to be flexed upon operation of the plunger of the solenoid.

Another object of the invention is the provision of an oil bath solenoid unit having an actuating rod extending outwardly of the unit to actuate a device to be operated by the unit, with an improved oil sealing means encircling the rod to prevent the escape of oil outwardly of the unit, or the entrance of any fluid from the device being operated into the oil bath solenoid unit, and which means is so constructed that any movement of fluid along the rod through the sealing means is visually evident upon inspection of the unit.

Another object of the invention is the provision in a solenoid of a spacer pin disposed between the plunger of the solenoid and a part to be actuated by the plunger, which pin will cushion the shock of the plunger and materially prolong the life of the solenoid.

Still another object of the invention is the provision of an automatic lead wire connector for a solenoid wherein the connector will not only automatically couple the lead wires to a source of electric current when the solenoid is mounted on a device to be actuated, but will also serve to effectively fluid-seal the entry of the lead wires to the solenoid.

Other objects, advantages, and meritorious features will more fully appear from the specification, claims, and accompanying drawing, wherein:

In the conventional solenoid there is provided a coil housed in a C-shaped or U-shaped frame. A plunger, generally T-shaped in configuration, is adapted to extend into the frame between the arms thereof and through the coil and lie in the plane of the frame with the underside of the head of the T-shaped plunger abutting the ends of the arms of the frame. Shading coils at the meeting faces of the underside of the head of the plunger and the ends of the arms conduct an out-of-phase current which tends to hold the plunger in a seated position against the ends of the arms of the frame. The shading coils function properly only so long as the underside of the head of the plunger and the ends of the arms of the frame abut each other throughout substantially their entire meeting surfaces. Once these meeting surfaces become peened or worn away, they permit the plunger to abut the bight portion of the frame and the contact between the head and the ends of the arms of the frame become uneven at the end of each arm. The shading coils then fail to function properly and the plunger chatters and eventually the coil burns out.

A second cause of failure of solenoids is their tendency to overheat after long and continuous operation. This overheating is due to the inability of the heat generated during the operation of the solenoid to be conveyed away from the solenoid as rapidly as it is generated. The surface area of the solenoid exposed to the atmosphere is too small to permit adequate heat transfer from the solenoid to the atmosphere.

We have provided a solenoid unit which substantially prolongs the life of the solenoid which forms a component of the unit because both of the above causes of

failure have been materially reduced if not eliminated. In carrying out the objects of our invention we provide an oil bath within which the solenoid operates, with the oil bath and the solenoid comprising a unit which may be mounted upon a device to be actuated. This unit, because it is capable of being mounted as such upon a device to be actuated, may be mounted in many different places, as, for example, in large machines, to actuate various parts of the machine. With the provision of our improved solenoid unit in which the solenoid will continue to function over a greater period of time than is presently possible with the conventional solenoids of today, the frequent repair of machinery embodying solenoids which are disposed in inaccessible places and whose failure causes breakdown of the machine, is materially reduced.

We have shown in Figs. 1 and 2 an illustrative embodiment of one form of our improved solenoid unit. The unit comprises a base 10 which is adapted to be mounted by means of the bolts 12 and 14 upon the device to be actuated by the solenoid. Such device is represented at 16 in the drawings and includes a stem 18 which leads to the operative mechanism in the device. The device is so constructed that upon urging of the stem 18 downwardly, the valve, switch, or whatever the mechanism of the device may be, will be actuated.

The base 10 is generally circular as shown in Fig. 1. The upper surface or face of the base is centrally recessed as at 20 to provide an upwardly opening well or the like. The sides of the well are defined by the annular wall 22 which extends upwardly from the floor 24 of the well. Centrally of the base 10 is an aperture 26 extending through the bottom wall 24 of the well and downwardly outwardly of the base. The bottom surface or face 27 of the base is adapted to rest against the device to be actuated and may be upwardly recessed as at 28 to accommodate the design of the device 16.

The base 10 is adapted to support the enclosure or housing 30 which houses the solenoid generally indicated at 32. The enclosure is supported upon the base by a plurality of screws or bolts 34, two of which are shown in Fig. 2. The enclosure 30 is generally cup-shaped and opens outwardly at that end connected to the base. An O-ring gasket or the like 36 is seated within a groove 38 formed in the side of the base, with the O-ring gasket adapted to bear against the enclosure and seal the connection between the enclosure and the base.

In order to seal effectively the opening of the enclosure, the supporting means 10 includes a flexible diaphragm 40 which cooperates with the supporting means to prevent the escape of oil within the enclosure outwardly of the solenoid unit. The diaphragm may be formed of sirvine, which is an artificial rubber somewhat like neoprene, embedded in and covering the opposite faces of a nylon web or the like. The neoprene-like rubber, as well as the nylon, is resistant to the destructive action of oil and therefore serves very well as a flexible seal for the unit. While a sirvine diaphragm has been mentioned specifically, it is to be understood that diaphragms of other materials might serve as well. The characteristics that the diaphragm must possess are that it must be formed of a material which will withstand the destructive effect of the fluid within the enclosure, it must be flexible enough so that it will not materially impede the movement of the plunger of the solenoid as hereinafter described, it must be capable of withstanding millions of flexures without cracking, it must be substantially unstretchable so that through prolonged use it will not become larger and larger, and it must be capable of receiving, as hereinabove described, a centrally disposed abutment member which is connected to the diaphragm, without a tendency to rip or tear at the point of connection of the bearing and guiding member with the diaphragm.

The diaphragm is generally circular in shape and

formed during its fabrication to exhibit an annular pleat or the like as at 42, which pleat is spaced from the perimeter of the diaphragm and adapted to be disposed within the well 20 of the base. The diaphragm, as shown in Fig. 2, is disposed inside of the enclosure 30 and is mounted upon the upper edge of the wall 22 of the well. It is disposed for flexure in the upwardly open recess or well. It is held against such upper edge and overlies the edge by an annular solenoid supporting plate 44 which bears against the diaphragm and is held thereagainst by a plurality of securing bolts or the like 46. It will be noted that the solenoid supporting plate serves a dual function of both supporting the solenoid and of securing the diaphragm to the base 10. When the bolts 46 are tightened down against the plate 44, they urge the same against the diaphragm and squeeze the diaphragm between the plate and the base 10. A sealing connection is thereby formed with the diaphragm against the base 10. It will also be noted that the O-ring gasket 36, the solenoid supporting plate 44, and the diaphragm 40 cooperate to seal the open end of the enclosure 30, and prevent the escape of oil within the enclosure outwardly of the solenoid.

The solenoid 32 shown in the drawings is of conventional construction. It may comprise a generally U-shaped frame, or what may be termed a C-stack 48 housing a solenoid coil 50. A solenoid plunger 52 generally T-shaped in cross section is adapted to reciprocate within the frame through the coil 50 under the influence of a magnetic field created by the coil. The top of the U-shaped frame may be bridged by a shock-absorbing element or the like 54 and against which the head portion 56 of the plunger bears when it returns upwardly from its retracted position. It is to be understood that when the coil 50 is energized the plunger is attracted downwardly, and when the coil is de-energized, the plunger is permitted to return to its uppermost position under the influence of a spring or the like in the device 16 to be actuated. The lower surface of the head portion 56 of the plunger is adapted to abut the upper ends of the U-shaped frame 48 along the line indicated in the drawings at 58. The head 56 is provided with shading coils which hold the head of the plunger against the upper ends of the arms of the frame. It will be noted in Fig. 2 that the plunger is in its retracted position downwardly in the frame and that the meeting surfaces of the underside of the head 56 and the upper edge of the U-shaped frame are in abutment along the line 56, and that the lower end 60 of the plunger is spaced a slight distance above the upper surface of the bottom of the U-shaped frame. It is apparent that if the meeting surfaces of the plunger and the U-shaped frame along the line 58 were to wear away sufficiently, the lower end 60 of the plunger would abut the upper surface of the bottom of the U-shaped frame. Such abutment would eventually tend to prevent the head 56 from properly seating upon the upper ends of the arms of the U-shaped frame, and when this occurs the shading coils fail to hold the plunger seated and the plunger will chatter. A chattering plunger is incapable of holding the same load as one which does not chatter. It tends to heat up and burn out the coil of the solenoid.

Received within the lower end of the U-shaped frame 48 and within the annular solenoid-supporting plate 44 is a bearing insert 62. The insert is provided with a shoulder 64 adapted to bear against the upper surface of the plate 44 and be disposed within a complementally shaped recess in the U-shaped frame 48. The solenoid frame is held down upon the supporting plate 44 in any convenient manner and grips the insert 62 between the frame and the plate.

The insert is provided with a central aperture 65 through which extends the short pin or rod 66 and which is supported in the insert in bearing relation therewith.

The insert is adapted to guide the movements of the pin 66 when the plunger 52 of the solenoid abuts the pin and urges it downwardly, or when the stem 18 of the device is urged upwardly under the influence of a spring or the like in the device. The aperture 65 in the insert 62 is in alignment with the aperture 26 in the base.

As shown in Fig. 2 the diaphragm is provided centrally thereof with an abutment member or a button 68. One form of the button is shown in detail in Fig. 3 and includes an upper annular plate 68-a and a lower annular plate 68-b provided with an upwardly extending boss 68-c adapted to be received through an aperture in the diaphragm and through an aperture in the upper plate 68-a. The two plates are held together and upon the diaphragm by the peened-over portion 69 of the boss 68-c. The upper plate 68-a and the lower plate 68-b are provided with annular complementally shaped ridge and groove equipments indicated in the drawing at 71 and 73 respectively. The diaphragm is adapted to be gripped between the ridge and groove equipments to ensure the retention of the button centrally of the diaphragm and in alignment with the aperture therethrough, through which extends the boss 68-c. The boss 68-c and the lower plate 68-b are adapted to withstand and transmit the forces between the pin 66 and the lower pin 70 hereinafter to be described. With the provision of the boss 68-c the upper plate 68-a is not compressed toward the lower plate 68-b and therefore the diaphragm is not squeezed between the plates during the action of the solenoid.

Disposed beneath the diaphragm is another pin 70 which is slidingly received within the aperture 26 in the base 10, and which is adapted to abut at its upper end the button 68 and at its lower end the stem 18 of the device 16 to be actuated. This pin is adapted to transmit the force of the plunger upon pin 66 and against button 68 to the stem 18 to urge the stem downwardly under the influence of the downward movement of the plunger. Pin 70 is also adapted to transmit the upward force of the spring in the device 16 against the stem 18 to the button 68, pin 66, and thence to the plunger 52, to urge the latter upwardly in the solenoid frame when the coil is de-energized.

Because of the provision of the pleat 42 in the diaphragm, the diaphragm may be flexed downwardly into the well 20 without tending to stretch the diaphragm. The fold of the pleat 42 is sufficient to accommodate the downward movement of the diaphragm.

The enclosure 30 is provided with an oil-filling aperture closed by a plug 72. The enclosure is also provided with an electric lead plug as at 74 which is provided with a pair of electric leads 76 and 78 which in any convenient manner are sealed within the plug 74 and extend therethrough into the inside of the enclosure as shown at 76' and 78'. Electric leads (not shown) connected at 76' and 78' extend to the coil 50 to electrically connect the same with the outside leads 76 and 78. The enclosure may be filled with oil as, for example, to the level indicated at 80. The oil found desirable for use in the enclosure has been conventional hydraulic brake fluid oil. Ordinary mineral oil has also been found to be very suitable. The prime requisites of the oil are that it must be capable of conveying heat from the solenoid to the walls of the enclosure and also be capable of acting as a lubricant for the meeting faces of the plunger and U-shaped frame 48, and for the other moving parts of the solenoid.

In the operation of the unit shown in Figs. 1 and 2, and assuming that the plunger 52 is in its retracted position upwardly against the upper inside surface of the buffer member 54, upon energization of the coil 50, the plunger will be attracted into the coil and downwardly toward the diaphragm. As the plunger moves downwardly through the oil filling the enclosure and nears

its downwardmost position, for example, when it is spaced substantially ".001" from the upper surface 82 of the frame 48, a thin film of the oil will exist between the meeting faces of the plunger head 56 and the surface 82. This thin film of oil tends to resist continued downward movement of the plunger. However, under the constant influence of the magnetic field created by the coil 50, this thin film of oil is almost squeezed out from between the meeting surfaces 82 of the frame. During this last increment of travel of the plunger in squeezing the oil film out from between the meeting surfaces, the plunger's downward movement is slowed almost to a complete stop. Its movement through this last ".001" of travel is very slow, such that when the plunger is finally seated against the upper face 82 of the frame, it is brought up against such face gently. Such gentle contact of the head 56 of the plunger with the upper surface 82 of the frame prevents the wearing away of these meeting surfaces and therefore prevents the plunger from chattering after long continued use.

The operation of the plunger from its extended to its retracted position may be very rapid because the cushioning effect of the oil film does not occur, for example, until the last ".001" of travel of the plunger. This rapid movement, as is well known by those skilled in the art, is important to the proper functioning and life of the solenoid, and therefore it is important that such movement be slowed only at the very end of the movement of the plunger.

In Fig. 5 is shown a modification of the abutment member. Such abutment member includes a stem portion 90 and a pair of centrally apertured disc-like elements or plates 92 and 94. The upper end of stem 90 has a reduced diameter portion 96 which extends through the elements 92 and 94, and forms a shoulder 97. The upper end of the reduced diameter portion 96 may be peened over as at 98 to secure the elements 92 and 94 in gripping engagement upon opposite sides of the diaphragm upon the end of the stem 90, with element 92 abutting the shoulder 97. Rib and groove equipments 101 and 103, similar to those described in connection with Fig. 3, are provided in the plates to prevent the diaphragm and abutment member from shifting relative to one another.

The lower end of the stem 90 is received within the aperture guideway 26 in the base 10. Its lower end is adapted to abut the upper end of the actuating rod 18 of the device to be actuated. Above the diaphragm, and adapted to abut the peened end 98 of the stem, is a spacer pin 102 which abuts at its upper end the plunger 52. The advantage of the construction shown in Fig. 5 over that shown in Fig. 3 is that the abutment member 92, and consequently the diaphragm, are guided during their reciprocal movements by virtue of the sliding fit of the stem 90 within the guide aperture 26. With the construction shown in Fig. 3, there is nothing which ensures movement of the abutment member and consequently the diaphragm along an axis perpendicular to the normal plane of the diaphragm. With the provision of the sliding fit of stem 90 in the aperture 26, the diaphragm is prevented from twisting at its center and therefore its life is prolonged because it is not subjected to undue stretching as it is flexed.

In Fig. 6 is shown still another modification of the button or abutment member shown in Fig. 3. In Fig. 6 the button or abutment member includes a stem 104 which is slidably received within the insert 62, with the lower end of such stem being received through a pair of centrally apertured discs, elements or plates 110 and 112 with the end of the stem being peened over to grip the plates between such end and the shoulder of the stem.

It is apparent that the construction shown in Fig. 6 is very much similar to that shown in Fig. 5 with the parts

reversed. A spacer element or actuating part 106 is slidably received within the base 10 and is adapted to abut at its lower end the actuating rod 18 and at its upper end the peened portion 108 of the stem 104. The plates 110 and 112 which are disposed on opposite sides of the diaphragm 40, grip the diaphragm with the rib and groove equipment, and are securely anchored to the diaphragm between the peened-over end 108 and the shoulder 109 of the stem.

The actuating part 106, it should be understood, may be eliminated if the stem of the device to be actuated extends sufficiently far into the base 10. It will also be noted that the insert 62 in Fig. 6 guides the movement of the stem 104 and consequently the movements of the diaphragm, and prevents twisting of the diaphragm.

The oil filling the enclosure is a much better conductor of heat than is air. The oil filling the enclosure is in intimate contact, as hereinabove mentioned, with all of the parts of the solenoid. Because of this any heat given off by the solenoid is conducted through the oil to the walls of the enclosure. The surface of the enclosure exposed to the atmosphere is of a much greater area than would be the surface of the solenoid if it was mounted in the atmosphere as are present-day solenoids.

Because there is a greater amount of surface exposed to the atmosphere in the instant construction there is a larger surface to transfer heat to the atmosphere. Therefore, our solenoid unit serves to conduct heat generated by the solenoid more rapidly into the atmosphere than is at present possible with the conventional solenoid. This materially increases the life of the solenoid because the solenoid will not heat up as much though it be used constantly and repeatedly over a long period of time.

Shown in Fig. 7 is a modified form of our invention which includes, as does the Figs. 1 and 2 embodiment, a closed housing in which a solenoid is disposed, with an oily fluid filling the housing and enveloping the solenoid. The unit comprises a base 120 having a solenoid-supporting surface 122 which is centrally recessed as at 124. A solenoid 126, having a supporting plate 128, is mounted, by means of screws 130, upon the base 120. The solenoid includes a plunger 132 which is adapted to reciprocate through the coil 134. The plunger has a shank portion 136 which extends through the coil, with the lower end of the shank adapted to abut the upper end of the spacer pin 138. The lower end of the spacer pin is adapted to abut the head 140 of the actuating rod 142 which extends through the base 120. The spacer pin slides within a bushing 144 mounted in the solenoid-supporting plate 128.

The base 120 is secured, as by means of bolts 146 or the like, to the device to be actuated 148. Various shaped bases may be employed to suit the particular application in which a solenoid unit is to be used. The head of the actuating rod 142 is disposed within the recess 124 in the base and moves therein from an extreme lower position to an extreme upper position.

Below the head 140 the rod is encircled by an improved sealing means, received within a counterbore in the base, and through which sealing means the rod reciprocates and is guided for reciprocation. Such sealing means comprises a bushing 150, shaped as shown in Fig. 7, and provided with a pair of axially spaced apart external grooves within one of which is received an O-ring gasket 152 adapted to bear against the wall of the counterbore within which the bushing is received. The other groove indicated at 154 communicates with a drain hole 156 extending through the base. An internal groove 158, concentric with groove 154, is formed in the bore 160 of the bushing, and communicates with groove 154 by means of a small cross aperture 162. A pair of O-ring gaskets 164 and 166 encircle the rod at opposite ends of the bushing seated within suitably provided recesses. The lower of these recesses may have a lip 168

to hold the O-ring 166 in place. The O-ring gasket 164 is adapted to form a fluid-tight seal about the actuating rod 142 and prevent the escape of oil from the solenoid chamber downwardly along the rod. The O-ring gasket 166 is adapted to form a fluid-tight seal and prevent any fluid that may be in the device 148 from creeping up along the actuating rod. In the event that fluid does creep by the O-ring gaskets, it will be collected in the internal groove 158 and from there will drain outwardly through the cross aperture 150 into the drain hole 156 and from there outwardly of the solenoid unit. Upon inspection of the solenoid unit it may be readily determined whether or not either of the O-ring gaskets 164 and 166 is defective, because if either is so, it will be noted that oil is escaping from the drain hole 156.

The lower end of rod 142 is adapted to abut or be coupled with that part of device 148 which is to be actuated. The device 148 may be provided with a spring or some other means not shown, which normally urges the part to be actuated toward the connecting rod 142. This spring or other means serves to maintain the rod and the plunger in a normally extended position, i.e., the plunger is moved to the dotted outline position in Fig. 7 with the head 168 in abutment with the cover 170. Upon energization of coil 134 the plunger is retracted or sucked into the coil to the solid outline position. This movement of the plunger into the coil is against the action of the spring or other means in the device to be actuated. When the electric current to the coil is interrupted, the plunger is immediately returned to the dotted outline position with the head 168 abutting the cover 170.

The cover 170 is received over the base 120 and sealed thereon in fluid-tight relation by the O-ring gasket 172 seated in a suitable groove in the base. Screws or the like 174 extend through the cover to secure it to the base. It will be noted that screws 174 extend through the cover and into the base below the O-ring gasket 172, and therefore the need for sealing the entry of the screws through the cover is eliminated. A filler opening 176 extends through the cover and is adapted to be closed by a suitable plug. The cover shown in Fig. 7 is adapted for use with a solenoid intended to be operated on its side, that is to say, the axis of movement of the plunger lies in a horizontal plane with the filler opening 176 on top. The drain hole 156 would then be disposed to open downwardly. The housing is filled with oil, as above described in connection with Figs. 1 and 2.

An electric lead wire 178 running from the coil 134 outwardly of the solenoid unit through the base and into the device to be actuated, is shown in Fig. 7. There are generally two such wires, but only one is shown for convenience, it being understood that the other wire is similarly disposed and arranged. Instead of extending into the device to be actuated, the lead wire may extend through the side of the base above the device. The wire is received through an aperture 180 in the solenoid-supporting plate as shown in Fig. 8, and through a hole 182, extending through the base 120. Just beneath plate 128 is a cone-shaped countersink 184, within which is disposed an O-ring gasket 186. Upon securing the solenoid-supporting plate 128 to the base, the gasket 186 is compressed in the countersink and is squeezed about the wire 178 to form a fluid-tight seal thereabout and between the wire and the base.

The spacer pin 138, mentioned above, is formed preferably of a somewhat resilient material such as nylon. We have discovered that a pin formed of this material rather than metal, will cushion the shock on the plunger when it moves downwardly to actuate the device 148. When a steel or brass pin is used, the plunger may not last for more than a few million cycles of operation, but with a nylon pin, the plunger may operate through many more times this number of cycles without showing evi-

dence of breaking up. In Fig. 9 a modified form of the pin 138 is shown. In this figure the pin has a body 190 formed of metal such as brass or steel, with a pair of nylon caps 192 and 194 at each end. In cross section these caps are generally T-shaped with the shank of the T press fitted within suitable recesses formed in opposite ends of the pin. This form of the pin is particularly suitable where the pin must be of a longer length or where it is desirable to have a metal-to-metal contact between the pin and the bushing 144.

In the operation of the solenoid unit shown in Fig. 7, the plunger, upon energization of the coil, is sucked into the coil with the spacer pin 138 and the oil in the housing dampening the shock. The manner in which the oil dampens the shock is explained hereinabove with respect to the construction shown in Figs. 1 and 2. Upon the return stroke of the plunger shown in Fig. 7, that is to say, upon the return from the solid outline position to the dotted outline position, the head of the plunger abuts the cover 170. The oil which fills the housing is squeezed out from between the head of the plunger and the cover, and slows the movement of the plunger to almost a complete stop at the very last increment of the plunger's movement, in a manner similar to the description of the dampening effect of the oil in connection with the Figs. 1 and 2 structure. It will be noted that in Fig. 2 the solenoid is shown as provided with a buffer element 54. In the Fig. 7 construction, the buffer has been eliminated and the oil serves as the buffer. Therefore, in the Fig. 7 construction the oil is relied upon to dampen the movements of the plunger at the opposite ends of its stroke.

In Fig. 10 we have shown an improved fluid-sealing lead wire connector particularly adapted for use with the oil bath solenoid unit of Fig. 7. The lead wire 178 in Fig. 7 is shown as extending from the coil 134 down through the base and into the device to be actuated. It is apparent that if it is desired to remove the solenoid from the base 120 it will be necessary either to cut the lead wire 178 or disconnect it somewhere below the base and pull it out of the wire-receiving hole 182; or if a solenoid is mounted on the base, that it is necessary to thread the lead wire down through the wire-receiving hole 182 to connect it somewhere to a source of electric current. The connector shown in Fig. 10 will eliminate the necessity of threading the lead wire into or out of the base in removing or replacing the solenoid, and yet will ensure a fluid-tight seal. As will be apparent, the connectors shown, while particularly adapted for use in an oil bath solenoid, will be equally useful and effective with conventional solenoids.

The connector includes a pair of bell-shaped gaskets 196 and 198 which may be formed of neoprene or other synthetic rubber-like material capable of withstanding the destructive effects of oil. Spacing the gaskets apart is a hollow body portion 200 of insulating material such as Bakelite, the ends of which are countersunk to conform to the tapering meeting surfaces of the gaskets 196 and 198. A pair of contacts 202 and 204 are disposed within the body and held tensioned apart by the resilient spring element 206 formed of an electrically conductive material. The lead wire 178 is cut short and contact 202 is secured to the end of it. To the cut end of the remainder of the lead wire 178, which remainder is indicated at 178-a, is secured the other contact 204. The gasket 196 is disposed beneath the solenoid-supporting plate with the neck 208 received within the aperture 180 of the plate. The base is counterbored as at 210 to receive the connector therein, with the bottom 212 of the bore serving as a shoulder upon which the gasket 198 rests, such that the connector is gripped between the bottom 212 of the bore and the solenoid-supporting plate when the plate is secured to the base. When the solenoid-supporting plate is tightened down upon the base, the gaskets 196 and 198 are squeezed against the connector body 200 and against the lead wires

178 and 178-a which extend through the gaskets, and an effective fluid-tight seal is formed about the wires.

It is apparent that upon removal of the solenoid and plate from the base, the gasket 196 and the contact 202 will be lifted out of the counterbore 210 and out of contact with the remainder of the connector, and an electric circuit through the connector will be broken. Therefore the source of electric current to the solenoid need not be interrupted while the solenoid is being removed, nor while it is being mounted on the base, as the workman need not touch a possible "hot wire." It is also apparent that this connector both forms a fluid-tight seal and also effectively electrically connects the lead wire 178 to the source of electric current, merely by inserting the contact 202 into the connector and tightening the solenoid and plate down upon the base.

Shown in Figs. 11-14 is another modification of our oil bath solenoid unit. This modification represents an improvement upon the modifications shown in Figs. 1-10, inclusive, and is adapted to automatically effect, when placed upon and secured to the device to be actuated, the mechanical actuating connection and electrical connection. The device to be actuated is provided with a part which a moving actuating rod means in the unit engages, and is also provided with electric lead wires extending up to that surface of the device upon which and over which the solenoid unit lies. The result of providing a unit of the character shown in Figs. 11-14 is that the attendance of two workmen to install or remove the unit is unnecessary. Under existing union regulations, when a solenoid is to be placed upon or removed from a hydraulic valve or the like, both an electrician and a hydraulics mechanic must be present, the former effecting or disconnecting the electrical connection, and the latter removing the screws or bolts which hold the solenoid to the device to be actuated. With the unit shown in Figs. 11-14, there are no electrical wires to be connected or disconnected which will require the attendance of an electrician, and therefore the unit may be installed or removed by only the hydraulics mechanic. This will effect a substantial saving in labor.

As shown in Fig. 11, the unit includes a closed housing within which is disposed a solenoid having a reciprocable plunger, with means positioning the solenoid within the housing, and with the housing filled with an oily fluid which envelops the solenoid. Actuating rod means extends outwardly of the housing and is adapted to engage at one end of the plunger of the solenoid and at the other end the movable part of the device to be actuated upon which the solenoid unit is mounted. Sealing means encircles the actuating rod means to prevent the escape of the oily fluid out of the housing along the actuating rod means. A pressure relief valve and an inspection drain are provided with the former serving to prevent bursting of the housing if the heat of the solenoid increases the pressure within the housing, and with the latter serving to indicate visibly any leakage of oily fluid out of the housing along the actuating rod means.

The housing is generally indicated at 220, and includes a base portion 222. Within and forming a part of the base portion 222 is a removable end wall 224, upon which and against which the solenoid, generally indicated at 226, is seated. The housing includes a cover 228 which is received over and cooperates with the end wall portion 224 to form a closed receptacle, enclosure, or housing.

As shown in Fig. 12 the cover 228 may be generally cylindrically shaped and is adapted to closely surround solenoid 226. The base portion 222 of the housing may be provided with outwardly extending flanges 230 through which bolts or the like 232 may be extended for the purpose of securing the unit to the device to be actuated. The solenoid 226 is supported, as shown in Fig. 13, upon a rubber cushion or the like 234, which overlies the end wall 224. The end wall may be provided with a pair of upstanding ears 236 between which the solenoid frame or C-stack 238 is received. The ears 236 serve to position

the solenoid rotation-wise within the housing. A coil spring 240 bears at its lower end against the upper edge of the C-stack and at its upper end against the underside of the cover 228, and tensions the solenoid down against the rubber cushion 234. Ears 236 and the rubber cushion 234 and the coil spring 240 provide means to resiliently support the solenoid within the housing. No bolts, screws, or the like are required to position the solenoid in the housing with the provision of ears 236, cushion 234, and the spring 240, and for this reason it is apparent that the mounting of the solenoid within the housing is of a simple character and that the solenoid may be readily assembled and disassembled within the housing.

The upper end of cover 228 may be provided with a boss or the like 242 through which is threadedly received a combination packing and bushing nut 244. A reset button 246, as shown in Fig. 13, is received through the nut 244 and upon being urged downwardly will move the plunger 248 of the solenoid downwardly, when the latter is in its uppermost position. The pin 246 may be provided with an annular groove within which is received an O-ring gasket 250 to seal the pin 246 within the nut. Suitable gasket means, such as a copper packing ring 252, may be received beneath the flange of nut 244 and the upper surface of boss 242.

The solenoid 226 is of conventional construction in that it includes, as mentioned above, a C-stack 238 consisting of a plurality of laminated generally U-shaped plates held together by rivets or the like, not shown, with a pair of plunger buffer frames 254 and 256 overlying opposite sides of the C-stack. Bolts or the like 258 extend through the C-stack and the frames to secure the frames to the stack. The upper ends of the frames are shaped as shown in Figs. 11 and 13 to provide buffer carrying ears 260 and 262. A buffer plate 264 extends through apertures in ears 260 and 262 with a neoprene or the like cushion 266 received within the U-shaped ends of the plate 264 to bear against the upper edge of the apertures or slots in ears 260 and 262, to thereby cushion plate 264 within the ears. For a more detailed description of the construction of this solenoid, reference should be made to the patent of H. W. Jencks #2,671,187. The plate 264 is provided with an aperture through which pin 246 may be extended to abut plunger 248.

The end wall 224 of the base portion of the housing is provided with an aperture extending therethrough and coaxially aligned with the reciprocatory movement of plunger 248. Received within such aperture is a bushing 268, with an O-ring gasket 270 disposed at the lower end of a counterbore of the aperture. The bushing 268 overlies the O-ring gasket to retain the same in the aperture. The O-ring gasket encircles actuating rod means 272 which is received for reciprocatory movement within the bushing 268. The O-ring gasket serves to prevent the passage of oily fluid in the housing outwardly therefrom along the actuating rod means 272.

Actuating rod means 272 includes a two-piece rod having a tool steel lower end portion 274 and a softer metal upper end portion 276. The upper end portion 60 may be formed of brass or beryllium copper. The beryllium copper or brass is a magnetic insulator and prevents the lines of flux from passing from the plunger directly down to the laminated plates at the bight of the C-stack. If this upper portion of the actuating rod means is of a magnetically conductive material, the sucking power of the solenoid would be materially reduced because the lines of flux could pass directly through the actuating rod means to the plates at the bight of the stack. The upper portion 276 may be provided with a reduced diameter portion 278 which is received within a complementary recess formed in the upper end of the tool steel portion 274. Portions 274 and 276 may be welded together as at 280.

The base portion 222 of the housing may be internally 70 provided with an encircling snap ring receiving groove

282 within which a snap ring 284 is received to hold the end wall 224 in place within the housing and against the action of coil spring 240. Cooperating shoulders indicated at 286 on the cover 228 and the end wall 224 position the end wall within the housing. An O-ring 288 received within a provided groove in end wall 224 cooperates with the cover 228 to seal the end wall in the housing.

The solenoid unit is shown as being mounted upon an adapter plate 290. The adapter plate is mounted upon the device to be actuated by the solenoid unit and adapts the device for mounting of the unit thereupon. In certain instances the adapter plate may be eliminated where the device to be actuated is especially designed for actuation by an oil bath solenoid unit of the character shown in Figs. 11-13. Once the adapter plate is mounted upon the device to be actuated, it may be considered an integral part of the device and is left affixed thereto when the solenoid unit is removed from the device for either servicing or replacement. The adapter plate includes an aperture 292 extending therethrough and into which the actuating rod means 272 extends. A visible inspection drain groove or the like 294 may be formed in the adapter plate to open at one end into the aperture 292 and open at the opposite end outwardly of the plate such that any leakage of oily fluid out of housing 222 by the O-ring gasket 270 will be visibly evident. In addition, any leakage of, for example, hydraulic fluid out of a valve or the like upon which the unit may be mounted, will also be evident upon inspection of groove or passageway 294.

A pressure relief valve comprising a spring-loaded ball member 296 may be received in a suitably provided recess in the end wall 224, with the ball serving to relieve excessive pressures developed within the housing through excessive heating of the oily fluid therein by a solenoid. The pressure relief valve communicates, as shown in Fig. 13, with the passageway 294.

In order to automatically effect an electrical connection between the solenoid unit and the device upon which the unit is mounted, when the unit is mounted upon such device, and effect an electrical disconnection of the unit when the same is removed from the device, cooperating electric terminal means are provided. Such cooperating electric terminal means comprises a male terminal 298 which is mounted within the end wall 224 of the base portion of the closed housing. A female terminal 300 is mounted within the adapter plate 290. The male terminal includes an insulated body portion 302 of rubber, neoprene, or the like, fixedly received within a provided aperture in the end wall 224. A pair of metal connectors 304 are fixedly received within the body portion 302, with screws 306 threaded into the connectors. Leads 308 connect the solenoid coil 310 to the connectors 304.

The female terminal portion 300 includes an insulating body 310 within which are received a pair of metallic connectors 312, as shown in Fig. 14. Electric leads 316 are connected with the connectors 312 and serve to electrically connect connectors 312 to a source of electric power. The leads 316 may extend into and through the device to be actuated. While only one electric lead 316 is shown, it will be understood that two are provided.

The adapter plate may be provided with a plurality of apertures 318 through which bolts or the like may be extended to secure the plate to the device to be actuated. Threaded apertures 320 are adapted to receive the bolts 322 for securing the unit to the adapter plate. Upon placing the solenoid unit upon the adapter plate with the male and female electric terminals interengaged, the actuating rod means 272 extends into aperture 292, in position to engage the part to be moved in the device to be actuated by the solenoid unit. The bolts 232 are tightened in apertures 320 to effect the securement of the unit to the device. Thus it will be seen that upon connecting the unit to the adapter plate mounted on the device to be

actuated, the electrical connection, and the mechanical connection with the part to be moved are simultaneously and automatically effected.

The inner walls of the cover 228 may be provided with increased thickness portions 322 having flat faces 324 adapted to both strengthen the cover and bear against the ears 236 to position end wall 224 rotation-wise within the cover 228.

What we claim is:

- 10 1. An oil bath solenoid adapted to be mounted as a unit upon a device to be actuated having a part to be shifted and fixed electric terminal means both located beneath the unit when the unit is mounted upon the device comprising, in combination: a closed housing including sealingly connected base and cover portions, means cooperating with one of said portions to secure the housing to the device to be actuated with the base portion juxtaposing said device, a solenoid disposed within the housing having a reciprocable plunger, means within the housing bearing against the solenoid and the housing to seat the solenoid upon said base portion, said base portion provided with an aperture therethrough, actuating rod means extending through the aperture to abut the plunger and be shifted thereby, fixed electric terminal means on said base portion with electric leads connecting such terminal means to the solenoid, an oily fluid filling the housing and enveloping the solenoid and bathing the plunger, gasket means encircling said actuating rod means and cooperating with the aperture to seal the rod means in the aperture, said actuating rod means and the electric terminal means on the base portion both adapted to engage, respectively, the said part to be shifted and the said fixed electric terminal means on the device to be actuated when the base portion juxtaposes the device.
- 20 2. An oil bath solenoid unit comprising, in combination: a closed housing having a base portion; a solenoid in the housing having a reciprocable plunger; said base portion provided with an aperture therethrough; actuating rod means extending through said aperture to be engaged and shifted by the plunger; means in said aperture cooperating with the rod means to seal the rod means in the aperture; an oily fluid in the housing enveloping the solenoid and bathing the plunger; electric terminal means on the base portion connected to the solenoid; and means to support the housing on a device to be actuated and having electric terminal means cooperable with the terminal means on said base portion to automatically effect an electric connection when the housing is placed on said supporting means and connected thereto, such latter means provided with an aperture through which said actuating rod means or a part to be actuated may extend; and means for connecting the housing to the supporting means.
- 30 3. The invention as defined in claim numbered 2 characterized in that the supporting means is provided with an aperture therethrough alignable with the aperture in said base portion, and said supporting means is provided with an inspection drain passageway opening at one end into the aperture through the supporting means and opening at the opposite end outwardly of the supporting means.
- 40 4. The invention as defined in claim numbered 2 characterized in that a relief valve is disposed in the housing with the discharge side thereof opening outwardly of the housing with the valve operable to relieve excessive pressure developing in the housing.
- 50 5. The invention as defined in claim numbered 2 characterized in that a relief valve is disposed on said base portion of the housing with the discharge side of the valve communicating with a drain passageway in said supporting means opening outwardly of the supporting means.
- 60 6. In an oil bath solenoid assembly for shifting a part to be actuated, an hermetically closed housing, a solenoid in the housing having a reciprocable plunger, actuating rod means sealingly extending through a wall of the housing and reciprocably supported therein in substantially coaxial alignment with the plunger and float-
- 70 75

ingly connected to the plunger to be shifted by the plunger upon energization of the solenoid, and an oily fluid filling the housing and enveloping the solenoid and bathing its plunger and the floating connection between the plunger and actuating rod means.

7. The invention as defined in claim 6 characterized in that a diaphragm cooperates with said actuating rod means and with the housing to prevent leakage of the oily fluid out of the housing around said actuating rod means.

8. An oil bath solenoid for removable securement to a device to be actuated having a part to be shifted, comprising, in combination: an hermetically sealed housing having an end portion for juxtaposition on the device to be actuated, a solenoid in the housing having a reciprocable plunger shiftable with respect to said end portion upon energization of the solenoid, actuating means extending sealingly through said end portion and supported therein for reciprocation substantially coaxially with respect to the plunger and floatingly connected at one end to said plunger to be shifted thereby upon energization of the solenoid and engaging at the other end the said part of the device to be actuated, an oily fluid filling the housing and bathing the solenoid and plunger and the floating connection between the plunger and said actuating means, and securing means adjacent said end portion for securing the housing to the device to be actuated.

9. An oil bath solenoid assembly as defined in claim 8 characterized in that said means floatingly connected at one end to the plunger is floatingly connected at the opposite end with the part to be actuated to shift the same.

10. An oil bath solenoid unit for removable securement to a device to be actuated having a part to be shifted, comprising, in combination: an hermetically sealed housing having opposite end wall portions with one end wall portion adapted for juxtaposition on the device to be actuated, a solenoid in the housing having a generally U-shaped flux conducting frame extending substantially normal to said one end wall portion, a solenoid coil in said frame seated at one end against the base of the U-shaped frame, the arms of said frame having portions extending over the opposite end of the coil and providing flat surfaces extending substantially normal to the axis of the coil, a reciprocable T-shaped plunger floatingly received in the coil and frame and shiftable substantially normal to said one end wall portion of the housing upon energization of the solenoid, the underside of the head of the T-shaped plunger having generally flat surfaces extending substantially normal to the reciprocating travel of the plunger and confronting said flat surfaces of the frame and abutting such surfaces at the end of the plunger's stroke upon energization of the solenoid to limit the travel of the plunger, said plunger having a length such in relation to the frame that when said surfaces are in abutting relation that end of the plunger opposite the head is spaced from the base of the frame, actuating means extending sealingly through one of said end wall portions of the housing and supported for reciprocation substantially coaxial with the plunger and floatingly connected at one end to said plunger to be shifted thereby upon energization of the solenoid and engaging at the other end the said part of the device to be actuated, an oily fluid filling the housing and bathing the solenoid and its plunger and said floating connection between the plunger and said actuating means and providing an oil film between said confronting surfaces, and means for removably securing the housing to the device to be actuated.

11. The invention as defined in claim 10 characterized in that said actuating means is a rigid pin-like member abutting that end of the plunger opposite the head end to be pushed outwardly of the housing upon energization of the solenoid coil.

12. The invention as defined in claim 10 characterized in that one of said end wall portions is removably seal-

ingly secured to the housing for removal or replacement of the solenoid in the housing and said actuating means comprises a rigid pin-like member extending sealingly through such removable end wall portion, and such end wall portion of the housing is adapted to juxtapose the device to be operated.

13. In an oil bath solenoid assembly for shifting a part to be actuated: an hermetically closed housing, a solenoid in the housing having a reciprocable plunger, actuating rod means extending sealingly through a wall of the housing and pushable outwardly of the housing by the plunger upon energization of the solenoid, an oily fluid filling the housing and bathing the solenoid and plunger, said actuating rod means pushable outwardly of the housing by fluid pressure in the housing acting against it, and a fluid pressure control valve communicating with the interior of the housing and vented to the atmosphere for allowing escape of excessive fluid pressure in the housing acting against said actuating rod means.

14. An oil bath solenoid assembly comprising, in combination: an hermetically sealed housing having a removable end wall, a solenoid in the housing having a flux conducting frame and a reciprocable plunger shiftable with respect to said frame upon energization of the solenoid, said end wall cooperating with the solenoid to position the solenoid in the housing, means extending sealingly through an end of the housing and supported in such end for reciprocation to be shifted by the plunger upon energization of the solenoid and floatingly connected to the plunger, and oily fluid filling the housing and bathing the solenoid and its plunger and said floating connection.

15. The invention as defined in claim 14 characterized in that said reciprocable means extends sealingly through the removable end wall of the housing.

16. An oil bath solenoid unit for removable securement to a device to be actuated having a part to be shifted and electric terminal means disposed adjacent said part, comprising, in combination: an hermetically sealed housing having an end portion for juxtaposition on the device to be actuated, a solenoid in the housing having a reciprocable plunger shiftable with respect to said end portion upon energization of the solenoid, actuating means extending sealingly through said end portion and supported thereby for reciprocation substantially coaxial with respect to the plunger and floatingly connected at one end to said plunger to be shifted thereby upon energization of the solenoid and engaging at the other end the said part of the device to be actuated, electric terminal means on said end portion of the housing electrically connected to the solenoid and disposed to be urged into engagement with said terminal means on the device to be actuated when said end portion of the housing juxtaposes such device and said actuating means engages said part to be shifted.

17. An oil bath solenoid unit for removable securement to a device to be actuated having a part to be shifted comprising, in combination: an hermetically sealed housing having at one end a removable wall, a solenoid in the housing having a flux conducting frame and a reciprocable plunger shiftable with respect to said frame and substantially normal to said removable wall upon energization of the solenoid, said frame and plunger having generally flat confronting surfaces extending substantially normal to the reciprocating travel of the plunger and substantially abutting each other at the end of the plunger's stroke upon energization of the solenoid to limit the travel of the plunger, actuating rod means extending sealingly through said removable wall and supported therein for reciprocation substantially coaxial with the plunger and floatingly connected at one end to said plunger to be pushed outwardly thereby upon energization of the solenoid and engaging at the other end the said part of the device to be actuated, said actuating rod

means pushable outwardly of the housing by fluid pressure in the housing acting against it, an oily fluid filling the housing and bathing the solenoid and its plunger and said floating connection between the plunger and said actuating rod means and providing an oil film between said confronting surfaces, a fluid pressure control valve in a wall of the housing communicating with the interior of the housing and vented to the atmosphere for allowing escape of excessive fluid pressure in the housing acting against said actuating rod means, and means for securing the housing to the device to be actuated with said removable wall substantially juxtaposing said device.

18. In an oil bath solenoid unit: a closed housing opening outwardly at one end and provided with an encircling wall surrounding the opening and an outwardly facing shoulder spaced inwardly from the open end, a circular end closure member removably received within the open end of the housing and seated against said shoulder, said closure member having a peripheral groove opening outwardly toward said encircling wall, a gasket in said groove cooperating with the groove and the encircling wall to hermetically seal the closure member in the open end of the housing, a solenoid in the housing, 25 spring means between the solenoid and one end of the housing holding the solenoid toward the opposite end of

the housing and tensioning said removable end closure member outwardly of the housing, and snap ring means cooperating with said encircling wall adjacent the open end of the housing and the closure member to hold the closure member in the open end of the housing counter the tension of said spring.
